MINING APPARATUS

Charles F. Osgood, Claremont, N. H., assignor to
 Sullivan Machinery Company, a corporation of
 Massachusetts

Continuation of application Serial No. 152,052,
 July 6, 1937. This application March 23, 1940,
 Serial No. 325,487

5 Claims. (Cl. 262—28)

This invention relates to mining apparatus, and more particularly to improvements in coal mining apparatus of the combined horizontal and shear cutter, track supported and guided type having improved adjustable kerf cutting mechanism.

An object of this invention is to provide an improved coal mining apparatus. Another object is to provide an improved coal mining apparatus having an improved adjustable supporting structure for the kerf cutting mechanism. A further object is to provide an improved adjustable kerf cutting mechanism for a coal mining apparatus of the combined horizontal and shear cutter type whereby the kerf cutter may be adjusted through a relatively wide range with respect to the coal face. Still another object is to provide an improved adjustable kerf cutting mechanism for a coal mining apparatus of the above character whereby kerfs may be cut in the coal face at any desired location between the mine roof and mine floor and between and in the ribs. A still further object is to provide an improved coal mining apparatus having novel arrangements and combinations of parts. Other objections will, however, subsequently more fully appear.

This application is a continuation of my application Serial No. 152,052, filed July 6, 1937, which has now become abandoned.

In the accompanying drawings there are shown for purposes of illustration two forms which the invention may assume in practice.

In these drawings—

Fig. 1 is a top plan view of a coal mining apparatus constructed in accordance with one illustrative embodiment of the invention.

Fig. 2 is a side elevational view of the coal mining apparatus shown in Fig. 1.

Fig. 3 is an enlarged view in longitudinal vertical section taken substantially on line 3—3 of Fig. 1.

Fig. 4 is a cross sectional view taken substantially on line 4—4 of Fig. 3.

Fig. 5 is a cross sectional view taken substantially on line 5—5 of Fig. 3.

Fig. 6 is an enlarged vertical sectional view taken substantially on line 6—6 of Fig. 1.

Fig. 7 is a horizontal sectional view taken substantially on line 7—7 of Fig. 6.

Fig. 8 is a diagrammatic view showing the hydraulic fluid system.

Fig. 9 is a top plan view of a coal mining apparatus constructed in accordance with a modified form of the invention.

Fig. 10 is a side elevational view of the mining apparatus shown in Fig. 9, with the cutter head rotated into top cutting position.

Fig. 11 is an enlarged horizontal sectional view taken substantially on line 11—11 of Fig. 10.

Fig. 12 is an enlarged cross sectional view taken substantially on line 12—12 of Fig. 10.

Fig. 13 is an enlarged view in longitudinal vertical section taken substantially on line 13—13 of Fig. 9.

Fig. 14 is a cross sectional view taken substantially on line 14—14 of Fig. 12.

Fig. 15 is a diagrammatic view showing the hydraulic fluid system.

10 In both illustrative embodiments of the invention, there is shown a coal mining apparatus of the combined horizontal and shear cutter, track supported and guided type, although it will be evident that various features of the invention may be incorporated in coal mining apparatus of various other types. Also, if desired, the mining apparatus may be tractor-tread supported and guided or supported for sliding movement on its own bottom over the mine floor and fed by flexible feeding means, in the manners well known to those skilled in the art.

15 In the illustrative construction shown in Figs. 1 to 8, inclusive, the reference character 1 designates a self-propelled portable base having mounted thereon a horizontal turntable 2 on which is supported the improved adjustable supporting structure, generally designated 3, for the kerf cutting mechanism 4. The portable base 1 may be of the same general character as that disclosed in a copending application of one Joseph F. Joy, Serial No. 20,826, filed May 10, 1935, now matured into Patent No. 2,229,087, patented January 21, 1941, although the self-propelled base may assume various other forms without departing from the spirit of the invention. The portable base 1 herein comprises a truck frame 5 mounted on wheels 6 adapted to run along a mine trackway 7. Supported on a horizontal truck frame portion 8 projecting forwardly in advance of the front truck wheels is the turntable 2 arranged in a relatively low position on the truck frame with its vertical axis of rotation disposed a substantial distance in advance of the front truck wheels. The forwardly projecting frame portion 8 of the truck frame supports annular bearings 9, in which a circular portion 10 of the upstanding frame 11 of the turntable is journaled, the turntable frame being held in position within its bearings by a bottom retaining ring 12 bolted to the bottom of the frame and underlying the horizontal frame portion 8, in the manner shown in Fig. 3. As disclosed in the above mentioned Joy application, the turntable may be rotated relative to the truck frame by means of a pair of parallel hydraulic cylinders 13, 13 supported on the truck frame at the rear of the turntable and containing reciprocable pistons having rearwardly extending piston rods 14 carrying brackets 15 supporting guide sleeves 16. Guided within an arcuate cable-receiving groove

17 formed about the upper outer edge of the turntable frame are cables 18, 18, these cables being fixed at one end to the turntable frame and passing around guide sheaves 19, 19 journaled on the truck frame at the rear of the turntable. The cables extend from the guide sheaves 19 rearwardly along the sides of the cylinders and around the guide sheaves 16, and are fixed at their other ends at 20 to the truck frame. When hydraulic pressure is supplied to one or the other of these cylinders, one of the pistons thereof moves to deflect one of the cables rearwardly, thereby to effect rotation of the turntable. By trapping the liquid in the cylinders, the pistons of these cylinders may be locked to hold the turntable against rotation. As is also described in the above mentioned Joy application, supported within the truck frame is a motor 21 having its power shaft connected through plural-speed transmission mechanism, to the truck wheels for propelling the apparatus in either of opposite directions along the mine trackway at either a relatively slow speed appropriate for cutting or a relatively high transport speed, and this motor also drives a hydraulic pump 22 arranged in a fluid reservoir 23 for supplying liquid under pressure to the various hydraulically operated devices of the apparatus, in the manner to be later explained.

Now referring to the improved adjustable supporting structure 3, it will be noted that pivotally mounted on a horizontal axis at 24 on the turntable frame for swinging movement in a vertical direction relative to the turntable is an elongated boom 25 comprising an inner or rear boom portion 26 and an outer or front boom portion 27. The outer boom portion is supported by the inner boom portion and is pivotally mounted on the outer extremity of the inner boom portion on a horizontal axis at 28, parallel with the pivotal axis 24, to swing in a vertical direction relative to the inner boom portion. In this instance, the rearward end of the inner boom portion 26 lies downwardly within the open center of the turntable frame and the pivotal axis 24 thereof is preferably located nearer the front edge of the turntable. The rearward end of the outer boom portion 27 has projecting side portions or arms 29 pivotally connected at 30 to rigid links 31 extending in parallel relation along the opposite sides of the inner boom portion and in turn pivotally connected at their rearward ends at 32 to the turntable frame. The axes of pivotal connection of the links with the turntable frame are parallel to the axes of pivotal connection of the links with the outer boom portion, and the link pivot axes are parallel to the pivotal axes 24 and 28 of the inner and outer boom portions. The points of pivotal connection of the links 31 with the turntable frame provide stationary restance points, so that when the inner boom portion is swung vertically about its pivotal axis relative to the turntable, the outer boom portion is always automatically simultaneously swung about its axis of pivotal connection with the inner boom portion, and, as a result, the outer boom portion swings in a vertical direction through a relatively greater angle than the angle of vertical swinging movement of the inner boom portion. It will thus be seen that when the inner boom portion is swung through a relatively small angle, the outer boom portion swings both with the inner boom portion and relative to the latter through a relatively great angle, and, as a result, the range of vertical adjustment of the kerf

cutting mechanism is greatly increased. Mounted on the outer boom portion 27 is a head 33 rotatable about an axis extending longitudinally of the outer boom portion at right angles to the pivotal axis 28, and pivotally supported on said rotatable head at 34 on an axis at right angles to the head axis, is a cutter support 35. Swivelled on the cutter support at 36 is a kerf cutter 37 of the kerf cutting mechanism. The rotatable head 33 comprises a tubular portion 38 journaled in a bearing sleeve 39 supported within a frame 40, the tubular portion 38 and the frame 40 constituting elements of the outer boom portion 27. Fixed to the tubular portion 38 is an annulus 41 having secured thereto a retaining ring 42 cooperating with an annular flange 43 formed on the outer end of the frame 40 for retaining the rotatable head in position on the latter. Fixed to the outer end of the tubular portion 38 of the rotatable head is a flanged member 44, to which is secured a flange 45 of a yoke-shaped frame 46. This yoke-shaped frame has side arms 47, 47 supporting bearing sleeves, in which are pivotally mounted cylindric trunnions 48 formed integral with the sides of the cutter support 35. Swivelly mounted on bearing sleeves supported by a cylindric bearing support 49 is an annular bearing portion 50 of a hanger frame 51. The kerf cutter 37 is in the form of an elongated plane cutter bar 52 carried by the hanger frame 51 and having guided for circulation about its margin an endless cutter chain 53. The hanger frame may be locked in different angular positions by a locking pin 54 guided on the cutter support and insertible in any one of a series of apertures 55 on the hanger frame 51.

The driving means for the endless cutter chain of the kerf cutter comprises a motor 56 mounted at the rearward end of the inner boom portion 26 and having its power shaft 57 arranged with its axis extending longitudinally of the inner boom portion. Keyed to the forward end of the motor power shaft is a coupling member 58 splined at 59 to a shaft 60 suitably journaled within the inner boom portion. Keyed to the forward end of the shaft 60 is a bevel gear 61 meshing, as shown in Figs. 3 and 4, with a bevel gear 62 keyed to a shaft 63 and rotatable upon an axis alined with the pivotal axis 28 of the outer boom portion. The shaft 63 is horizontally disposed and extends transversely of the inner boom portion and is suitably journaled in bearings supported thereby. The bevel gear 62 meshes with a bevel gear 64 keyed to a shaft 65 suitably journaled within the outer boom portion and in turn having keyed thereto at its forward end a bevel gear 66. As shown in Fig. 7, the bevel gear 66 meshes with a gear 67 in turn meshing with a gear 68 keyed to a shaft 69, herein alined with the pivotal axis of the cutter support 35. The gear 68 and shaft 69 are suitably journaled within one of the yoke frame arms 47 and the adjacent cutter support trunnion 48, as shown in Fig. 7, and secured to and driven by the shaft 69 is a bevel gear 70 meshing with a bevel gear 71 journaled on a shaft 72 alined with the kerf cutter pivot and connected to the shaft by a disc clutch 73. This clutch is set at a predetermined load and is adapted to slip upon overloading of the cutter chain, automatically to disconnect the shaft 72 from the gear. The shaft 72 is suitably journaled within the cutter support 35 and has keyed thereto, and drives, a chain sprocket 74 which engages and drives the endless cutter chain 53. Due to the particular arrangement of

the driving gears with respect to the pivotal axes chain 53. Due to the particular arrangement of the driving gears with respect to the pivotal axes of the outer boom portion, rotatable head, tilt-able cutter support and swivelled hanger frame for the cutter bar, the cutter chain may be driven by the motor 56 irrespective of the adjusted position of the various parts.

The hydraulically operated means for swinging the boom 25 in a vertical direction relative to the turntable, for rotating the cutter head 33 and for swinging the cutter support 35 relative to the cutter head, will now be described. As shown most clearly in Fig. 3, pivotally mounted on a horizontal shaft 77 supported within brackets 78 integral with the turntable frame near the forward edge of the turntable, are hydraulic lifting cylinders 79. The shaft 77 also preferably provides a pivotal support for the rear ends of the parallel links 31, 31, and the cylinders, in this instance, are therefore swingable in vertical planes about an axis coincident with the pivot 32 of the links. Reciprocable in the cylinders 79 are pistons 80 having their piston rods 81 extending forwardly and upwardly through the packed upper heads of the cylinders. The outer ends of the piston rods are pivotally connected at 82, on axes parallel with the pivotal axes of the cylinders, to depending lugs 83 formed integral with the bottom front portion of the inner boom portion 26. It will be evident that the relation of the axes of pivotal connection of the boom parts, the links, lifting cylinders and piston rods and the arrangement of the parts, may be varied without departing from the spirit of the invention. When hydraulic pressure is supplied to one end or the other of the cylinders 79, the boom 25 may be swung either upwardly or downwardly about its pivotal axis relative to the turntable, and when liquid is trapped within these cylinders, the boom may be locked in its adjusted position. The cutter head rotating means comprises, as shown most clearly in Fig. 5, a reversible hydraulic motor 85 of a conventional design, having its power shaft connected to a shaft 86 suitably journaled within the boom frame 40 and having fixed thereto and driving a worm 87 meshing with a worm wheel 88 formed on the annulus 41 of the cutter head. When the worm gearing is driven by the motor 85, the cutter head may be rotated in its bearing on the boom frame 40, and the worm gear teeth are self-locking for automatically locking the cutter head in its adjusted position. The swinging means for the cutter support 35 comprises a hydraulic cylinder 90 pivotally mounted at 91, on an axis parallel to the cutter support pivot axis, on aligned pivot pins 92 supported within projecting brackets 93 formed integral with the cutter head annulus 41. This cylinder contains a reciprocable piston 94 having its piston rod 95 extending forwardly through the packed front head of the cylinder and pivotally connected at 96, on an axis parallel to the pivotal axis of the cylinder, to projecting arms 97 formed integral with the cutter support frame, in the manner shown in Fig. 6. When hydraulic pressure is supplied to one end or the other of the cylinder 90, the piston may be moved to swing the cutter support in one direction or the other about its pivot relative to the cutter head, and by trapping the liquid within the cylinder, the cutter support may be locked in its adjusted position.

The hydraulic fluid system for supplying hydraulic pressure to the various hydraulically op-

erated devices, as shown in Fig. 8, comprises a conduit 100 leading from the discharge side of the pump 22 to the supply passage of a valve box 101 mounted on the truck frame. A discharge conduit 102 leads from the discharge passage of the valve box back to the reservoir 23. Contained in the valve box are control valves 103, 104, 105 and 106, each having an operating handle. The bore containing the valve 103 is connected by conduits 107 and 108 to the forward ends of the turntable rotating cylinders 13, 13, while the rear ends of these cylinders are connected by a conduit 109 for draining back to the reservoir any liquid leaking past the pistons to the rear ends of the cylinders. The bore containing the valve 104 is connected by conduits 110 and 111 to the opposite ends of the boom swing cylinders 79, 79. The bore containing the valve 105 is connected by conduits 112 and 113 to the opposite sides of the reversible head rotating motor 85, while the bore containing the valve 106 is connected by conduits 114 and 115 to the opposite ends of the tilting cylinder 90 for the cutter support. It will thus be seen that the valves may be operated to supply liquid pressure to one or the other of the cylinders 13, 13, to either end of the cylinders 79 and 90 and to either side of the reversible motor 85, by connecting certain of the conduits to the supply passage of the valve box and the others to the discharge passage. The particular valve box structure may be similar to that described in the above mentioned Joy application.

The general mode of operation of the form of the invention above described is as follows: The apparatus may be propelled along the mine trackway from one working place to another and during the cutting operation, through the truck wheel propelling mechanism driven by the motor 21, in the manner clearly described in the above mentioned Joy application. When the working place is reached and it is desired to cut a horizontal kerf at the floor level in accordance with the arcwall method of cutting, the turntable 2 and the boom 25 may be adjusted relative to the base to locate the kerf cutter at one side of the mine trackway at the level of the mine floor, with the tip end of the kerf cutter at the coal face near the right hand rib. The motor 56 may then be operated to effect circulation of the cutter chain about the margin of the cutter bar of the kerf cutter, and, upon propulsion of the apparatus bodily forwardly along the mine trackway, the kerf cutter may be dumped beneath the coal. Upon completion of the dumping cut, the truck wheels are braked, in a known manner, to hold the base stationary with respect to the trackway, and one of the turntable rotating cylinders 13, 13 is operated to rotate the turntable 2, thereby to effect swinging of the kerf cutter horizontally in its plane about the turntable axis across the front end of the base to effect the transverse cutting operation. When the tip end of the kerf cutter assumes a position adjacent the left hand rib and the swinging cut is completed, the truck wheel brake is released and the apparatus is propelled bodily rearwardly along the mine trackway to effect withdrawal of the kerf cutter from beneath the coal. When it is desired to insert a horizontal kerf in the coal face at the roof level, hydraulic pressure is supplied to the lifting cylinders 79, 79 to swing the boom 25 in a vertical direction about its pivotal axis 24 relative to the turntable, the outer boom portion 27 swinging about its pivotal axis 28 relative to the inner

boom portion as the boom is swung vertically. As the boom swings vertically, the cutter head 33 may be rotated about its axis relative to the outer boom portion to adjust the kerf cutter from the bottom cutting position indicated in dotted lines in Fig. 2 to the top cutting position likewise indicated in dotted lines in that figure. By the provision of the parallel links 34, 34 connecting the rearward end of the outer boom portion to the turntable frame, the outer boom portion not only swings in a vertical direction with the inner boom portion, but also swings simultaneously about its pivot relative to the inner boom portion, and, as a result, the range of vertical adjustment of the kerf cutter is greatly increased. When the 10 kerf cutter assumes its top cutting position, the apparatus may be operated to effect sumping, swinging and withdrawal movements of the kerf cutter in accordance with the arcweld method of cutting, in the same manner as that described above in regard to the bottom cut at the floor level. When it is desired to insert horizontal kerfs in the coal face at any desired location between the mine floor and mine roof, the lifting cylinders 79, 79 may be operated to swing the boom and the cutter support 35 may be swung about its pivot relative to the boom, thereby to 15 adjust the kerf cutter through a series of parallel horizontal cutting planes. By rotating the cutter head 33 about its axis relative to the boom, the kerf cutter may be adjusted from its top cutting position above the head axis, as indicated in full lines in Fig. 2, to a horizontal cutting position below the head axis, as indicated in dotted lines in that figure. In any of the horizontal cutting positions above described, the kerf cutter may be tilted into angularly related cutting planes with respect to the horizontal by operating the cutter support swinging cylinder 90 to 20 swing the cutter support either upwardly or downwardly about its pivot relative to the cutter head and boom. Furthermore, during any of the horizontal cutting operations above described, the kerf cutter may be rocked with the cutter head about the head axis relative to the boom to enable the kerf cutter to follow an uneven or rolling bottom or pitching coal seam. When it is desired to insert a vertical shear cut in the coal face, the cutter head 30 may be rotated to adjust the kerf cutter into a vertical cutting position with respect to the boom. The 25 turntable 2 may then be rotated relative to the base, and the cutter support 35 swung about its pivot relative to the cutter head to locate the kerf cutter in a vertical cutting position, as indicated in dotted lines in Fig. 1. The boom may then be swung upwardly relative to the turntable by the lifting cylinders 79, 79, until the tip end of the kerf cutter assumes a position at the roof level. The apparatus may then be propelled bodily forwardly along the mine trackway to sump the kerf cutter within the coal. The truck wheels of the base may then be braked to hold the base stationary with respect to the trackway, and the lifting cylinders 79, 79 may then be operated for 30 swinging the boom downwardly in a vertical direction relative to the turntable to move the kerf cutter in a substantially upright arcuate path to effect a vertical swinging cut. When the tip end of the kerf cutter assumes a position at the floor level and the swinging cut is completed, the truck wheel brake may be released and the apparatus propelled bodily rearwardly along the mine trackway to effect withdrawal of the kerf cut-

ter from the coal. By adjusting the turntable, boom, cutter head and cutter support about their respective pivotal axes, the kerf cutter may be adjusted into positions to cut horizontal and vertical kerfs in either rib at either side of the coal face, in an obvious manner. In any of the cutting operations above described, the angular relation of the kerf cutter with respect to the cutter support may be changed by releasing the locking pin 54, swinging the kerf cutter about its swivel mounting on the cutter support and thereafter relocking the kerf cutter to the cutter support.

In the modified form of the invention disclosed in Figs. 9 to 15, inclusive, the improved adjustable supporting structure for the kerf cutting mechanism is embodied in a coal mining apparatus of the same general character as that described in the British Patent 427,881 of 1935, thereby eliminating from the British structure the double pivot for the boom on the turntable, the pivoted side arms and the rear tilting cylinder by which the boom may be tilted downwardly into a position wherein the kerf cutter is supported at the floor level. In this illustrative construction, the portable base is generally designated 120, the turntable 121, the adjustable supporting structure generally designated 122 and the kerf cutting mechanism 123. The portable base 120 is in the form of a truck frame 124 supported on truck wheels 125 adapted to run along a mine trackway 126. As shown most clearly in Fig. 12, the turntable 121 has a circular portion 127 suitably journaled within bearings supported within an upstanding bearing support 128 formed on the truck frame. A king pin 129 extends loosely through a central opening at the center of a bearing retainer 130. Mounted on the truck frame is a bracket frame 131 which carries a series of horizontal pins on which are journaled supporting rollers 132 engaging an annular track 133 arranged concentrically with the vertical axis of the king pin and fixed to the bottom of the turntable. It will thus be seen that the turntable occupies a horizontal plane on the truck frame by means of the rollers engaging the track. The means for rotating the turntable relative to the truck frame comprises parallel hydraulic cylinders 134, 134 mounted on the truck frame and containing reciprocable pistons 135 having their piston rods 136 extending forwardly through the packed front heads of the cylinders. Secured to the piston rods are rack bars 137, 137 guided along slide bearings 138 and meshing with the teeth of a spur gear 139 secured to the turntable. When hydraulic pressure is supplied to the hydraulic cylinders, the pistons 135 are moved in opposite directions, thereby rotating the spur gear 139 to effect rotation of the turntable. When hydraulic pressure is trapped within these cylinders, the turntable is locked against rotation relative to the truck frame. Mounted on the truck frame at the rear of the turntable is a motor 140 adapted to drive, through a transmission mechanism generally designated 141, the truck wheels to propel the apparatus in either of opposite directions along the mine trackway at a relatively slow speed appropriate for cutting and a relatively high transport speed. Driven by the motor is a pump 142 adapted to supply liquid under pressure from a reservoir 143 to the various hydraulically operated devices, as hereinafter described.

Now referring to the improved adjustable sup-

porting structure 122, it will be noted that overlying the turntable 121 is an elongated boom 145 comprising a rear or inner boom portion 146 pivotally mounted at 147 on a horizontal pivot shaft 148 supported within upstanding brackets 149 formed on the rearward portion of the turntable frame. Pivotally mounted at 150 on the forward portion of the rear boom portion to swing relative thereto is a front or outer boom portion 151. Mounted on the front boom portion for rotation about the longitudinal axis thereof is a rotatable head 152, in turn having pivotally mounted thereon at 153 on an axis at right angles to the head axis, a cutter support 154. Pivotally mounted on the cutter support to swing relative thereto about an axis at right angles to the cutter support axis is a kerf cutter 155 of the kerf cutting mechanism. Pivotally connected at 156 to projections 157 integral with the rearward portion of the outer boom portion 151 is a pair of rigid links 158, 158 herein of curved form and extending rearwardly along the opposite sides of the rear boom portion 146. These links are pivotally connected at 159 at their rearward ends on the brackets 149. The rigid links 158 provide stationary reactance points at their points of pivotal connection with the brackets 149, so that when the boom is swung in a vertical direction about its pivot 147 relative to the turntable, the outer boom portion 151 is swung in a vertical direction about its pivot 150 relative to the rear boom portion 146, and, as a result, the outer boom portion swings through a substantially greater angle than the angle of swinging movement of the rear boom portion, thereby increasing the range of vertical adjustment of the kerf cutting mechanism. The rotatable cutter head 152 comprises a tubular frame portion 160 journaled on bearing sleeves supported by a tubular frame portion 161, rigidly secured to the rear frame 162 of the outer boom portion 151. The tubular frame portion 160 has an annular flange 163 having bolted thereto an annulus 164, and a retaining ring 165 cooperates with a flange 166 on the rear boom frame 162 for retaining the tubular head frame in its bearings in the boom frame. Formed integral with the forward portion of the tubular head frame 160 is a circular frame 167, in which is rotatably mounted a circular frame 168 secured to the cutter support 154. The ends of the circular frame portion 167 are covered by end bracket plates 169 which are spaced apart by a circular cross plate 170 and are attached, by means of screws, to the inner circular frame portion 168. A hanger frame 171 is journaled on a bearing sleeve supported by a circular bearing support 172, which is secured, by means of screws, to the cross plate 170. Carried by the swivelled bar hanger 171 is an elongated plane cutter bar 173 having guided for circulation about its margin an endless cutter chain 174.

Now referring to the driving means for the cutter chain, it will be noted that carried by the rear boom portion is a motor 175 having its power shaft 176 extending longitudinally of the rear boom portion. Keyed to the forward end of the motor power shaft is a bevel gear 177 meshing with a bevel gear 178 journaled on a cross shaft 179 herein arranged with its axis alined with the pivotal axis 150 of the front boom portion. The gear 178 meshes with and drives a bevel gear 180 keyed to a shaft 181, herein suitably journaled within the tubular portion 161 of the boom frame, and arranged with its axis

extending longitudinally of the outer boom portion. Keyed to and driven by the shaft 181 is a bevel gear 182 meshing with a bevel gear 183 (see Fig. 14). The bevel gear 183 is provided with a hub 184 which is journaled, by means of thrust bearings 185, on a shaft 186. One end of this shaft is journaled in a bearing 187, while the other end of the shaft is provided with a cap 188, which is secured in place by screws, and the cap 188 is journaled in a bearing 189 which is in the form of a hub extending outwardly from the left hand plate, as viewed in Fig. 14. The bevel gear 183 meshes with and drives a bevel gear 190 keyed to a shaft 191 to the outer end of which is keyed 15 a sprocket 192 which engages and drives the endless cutter chain. The upper end of the sprocket shaft 191 is provided with a cup-shaped cap 193, which is held in place by a screw, and between the lower end of the cap and a collar 194 is a roller thrust bearing 195, the outer race of which rests on an annular seat of a support 196 formed on the shaft 186. The shaft 191 is journaled, near its opposite end, in adjacency to the cutter chain sprocket, in a bearing 197 supported by the bearing support 172. It will thus be seen that the various driving gears and shafts are so arranged with respect to the pivotal axes of the outer boom portion, rotatable head, tiltable cutter support and swivelled cutter bar, that the cutter chain may be driven irrespective of the adjusted positions of the parts.

The means for swinging the boom 145, rotating the cutter head 152, and swinging the cutter support 154 and cutter bar hanger 171 will now be described. As shown most clearly in Fig. 12, pivotally mounted at 200 on alined horizontal axes at the opposite sides of the rear boom portion are upstanding hydraulic cylinders 201, 201 containing pistons 202 having their piston rods 203 extending downwardly through the packed lower heads of the cylinders and pivotally connected at 204 to the frame of the turntable 121. When hydraulic pressure is supplied to one end or the other of the cylinders 201, the latter may be moved relative to the pistons to swing the boom either upwardly or downwardly about its pivotal axis 147 relative to the turntable. As the boom swings vertically relative to the turntable, the outer boom portion 151 swings in a vertical direction about its pivot 150 relative to the rear boom portion 146, due to the rigid reactance links 158 connected between the front boom portion and the brackets 149 of the turntable frame, so that the outer boom portion swings through a substantially greater angle than the angle of swinging movement of the rear boom portion. When hydraulic pressure is trapped within the cylinders 201, the boom may be locked in its adjusted position. The cutter head rotating means comprises a reversible hydraulic motor 205 (Fig. 9) having its power shaft connected through worm gearing including worm wheel 206 (see Fig. 13) formed on the annulus 164 of the cutter head frame. When hydraulic pressure is supplied to the motor 205, the cutter head 152 may be rotated about its axis relative to the boom, and the self-locking teeth of the worm gearing lock automatically the cutter head in its adjusted position. The swinging means for the cutter support 154 comprises a hydraulic cylinder 207 secured to the outer boom frame and containing a reciprocable piston 208 having its piston rod 209 extending forwardly through the front packed head of the cylinder. 70 The piston rod is pivotally connected at 210, at

its forward end, to a sliding cross head guided in guideways 211 formed on the boom frame. This cross head is pivotally connected to parallel links 212, in turn pivotally connected at 213 to the cover brackets 169 secured to the tiltable cutter support frame. When hydraulic pressure is supplied to one end or the other of the cylinder 207, the piston 208 may be moved to swing the cutter support in one direction or the other relative to the cutter head, and when liquid is trapped within this cylinder, the cutter support may be locked in its adjusted position. The means for swinging the hanger frame 171 for the cutter bar about its pivot relative to the cutter support comprises a pair of hydraulic cylinders 215, 216 containing reciprocable pistons having their piston rods 216 extending forwardly through the front packed heads of the cylinders. The cylinders 215 are pivotally mounted at 217, on axes parallel to the bar pivot axis, on brackets 218 secured to the cutter support frame, and the piston rods are pivotally connected at 219 on parallel axes to projecting lugs 220 formed integral with the cutter bar hanger frame. When hydraulic pressure is supplied to the cylinders 215, the cutter bar may be swung about its pivot relative to the cutter support in one direction or the other, and by trapping the liquid within the cylinders, the cutter bar may be locked in its adjusted position.

The hydraulic fluid system for supplying hydraulic pressure to the various hydraulically operated devices, as shown in Fig. 15, comprises a conduit 225 leading from the discharge side of the pump 142 to the supply passage of a valve box 226 supported on the truck frame. The discharge passage of the valve box is connected by a discharge conduit 227 back to the reservoir 143. Contained in the valve box are control valves 228, 229, 230, 231 and 232, each having an operating handle. The bore containing the valve 228 is connected by a conduit 233 to the opposite ends of the turntable rotating cylinders 124 and by a conduit 234 to the other ends of these cylinders. The bore containing the valve 29 is connected by a conduit 245 to the opposite ends of the bar swinging cylinders 215 and by a conduit 236 to the other ends of these cylinders. The bore containing the valve 230 is connected by conduits 237 and 238 to the opposite ends of the boom lifting cylinders 201, while the bore containing the valve 231 is connected by conduits 239 and 240 to the opposite sides of the head rotating motor 205. The bore containing the valve 232 is connected by conduits 241 and 242 to the opposite ends of the cutter support tilting cylinder 207. It will thus be seen that the valves may be operated to supply liquid under pressure to the various hydraulically operated devices to operate the same in either of opposite directions, so that the parts adjusted thereby may be moved in either of opposite directions, and by trapping the liquid pressure within the cylinder and piston devices, the parts may be locked in their adjusted position. The valve box 226 and the control valves may be similar to those described above in regard to the other embodiment of the invention.

The general mode of operation of this embodiment of the invention is as follows: The apparatus may be propelled along the mine trackway from one working place to another and during the cutting operation, through the propelling mechanism 141 driven by the motor 140, in the manner clearly described in the

above mentioned British patent. The apparatus may be operated to cut horizontal and vertical kerfs at any desired location in the coal face between the mine roof and mine floor and between and in the ribs in the same general manner as that described above in the other embodiment of the invention. During any of the horizontal and vertical cutting operations, the kerf cutter, in this construction, may be swung by power about its pivot relative to the cutter support. As the boom 145 is swung either upwardly or downwardly about its pivot 147 relative to the turntable 121, the outer boom portion 151, due to the parallel reactance links 158 connecting the front boom portion to the turntable frame, swings not only in a vertical direction with the inner boom portion 146, but also in a vertical direction about its pivot 150 relative to the inner boom portion, and, as a result, the outer boom portion swings through a substantially greater angle than the angle of swing of the inner boom portion. Consequently a relatively wide range of vertical adjustment of the kerf cutter is possible with a relatively small range of vertical adjustment of the boom lifting cylinders 201. In this form of the invention, by the provision of the joint between the front and rear boom parts and the parallel reactance links, it is possible to eliminate the side arms, front boom pivot and rear boom tilting cylinder of the construction described in the British patent, since, in the present construction, as the boom swings downwardly toward the turntable, the front boom portion 151 automatically assumes a position at a substantial angle downwardly inclined relative to the rear boom portion, thereby enabling positioning of the kerf cutter at the floor level, as shown in the lower dotted line position in Fig. 10. Also, as the boom is swung upwardly relative to the turntable, the outer boom portion automatically assumes a position at an angle upwardly inclined relative to the inner boom portion, thereby increasing the vertical range of adjustment of the boom disclosed in the British patent.

As a result of this invention, it will be noted that an improved coal mining apparatus is provided having an improved adjustable supporting structure for the kerf cutter whereby a relatively wide range of vertical adjustment of the kerf cutter is possible. It will further be noted that by forming the boom in two parts joined together and by connecting the outer boom part by parallel reactance links to relatively stationary points, it is possible to adjust the kerf cutter through a relatively wide range with a relatively small range of adjustment of the boom elevating cylinders, while at the same time the point of support of the kerf cutter moves inwardly toward the center of the turntable, as the boom swings vertically, thereby decreasing the overhang of the boom with respect to the base as the vertical adjustment of the kerf cutter is increased. Other uses and advantages of the improved coal mining apparatus will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In combination, a cutter bar, a cutter bar supporting head, a pivotal mounting for said bar on said head, an elongated outer boom section providing a pivotal mounting for said head on an axis extending transversely to the length of said boom section and parallel to the planes of bar swing upon the pivotal mounting of the bar on the head, and means for supporting and swinging said outer boom section and providing automatically for augmented swinging thereof including an elongated inner boom section, means providing a horizontal pivotal mounting for the latter at its inner end, means pivotally connecting the inner end of the outer boom section to the outer end of the inner boom section on a parallel pivot, an elongated tie-forming element connected to the outer boom section at a point above the pivotal connection of the latter with the inner boom section and at a spaced point having a stationary pivotal support in spaced relation to the pivot for the inner boom section, and means for swingingly raising and lowering the inner boom section including hydraulic cylinder and piston devices pivotally connected to the inner boom section and to a stationary point of reaction.

2. In combination, a cutter bar, a cutter bar supporting head, a pivotal mounting for said bar on said head, an elongated outer boom section providing a pivotal mounting for said head on an axis extending transversely to the length of said boom section and parallel to the planes of bar swing upon the pivotal mounting of the bar on the head, and means for supporting and swinging said outer boom section and providing automatically for augmented swinging thereof including an elongated inner boom section, means providing a horizontal pivotal mounting for the latter at its inner end, means pivotally connecting the inner end of the outer boom section to the outer end of the inner boom section on a parallel pivot, a tie-forming element connected to the outer boom section at a point above the pivotal connection of the latter with the inner boom section and at a spaced point having a stationary pivotal support in spaced relation to the pivot for the inner boom section, and means for swingingly raising and lowering the inner boom section including expandible chamber thrust-exerting devices pivotally connected to the inner boom section at a point below the connection to the latter of said outer boom section and to a stationary point of reaction.

3. In combination, a cutter bar, a cutter bar supporting head, a pivotal mounting for said bar on said head, an elongated outer boom section providing a pivotal mounting for said head on an axis extending transversely to the length of said boom section and parallel to the planes of bar swing upon the pivotal mounting of the bar on the head, and means for supporting and swinging said outer boom section and providing automatically for augmented swinging thereof including an elongated inner boom section, means providing a horizontal pivotal mounting for the latter at its inner end, means pivotally connecting the inner end of the outer boom section to the outer end of the inner boom section on a parallel pivot, means for swinging the inner boom section in vertical planes upon its pivotal mounting including a cylinder pivotally supported on an axis parallel to and in fixed spaced relation to the pivotal support for the inner boom section,

and a piston pivotally connected with said inner boom section, and link means pivotally connected at one end on an axis in the same straight line with the pivotal support for said cylinder and at its other end pivotally connected with the inner end of the outer boom section upon an axis above the connection of the latter with the inner boom section.

4. In a mining apparatus, a portable support, a rearward boom section, means for supporting said rearward boom section for vertical swinging movement about a horizontal pivot axis adjacent its rear end arranged at a fixed height upon said portable support, a front boom section pivotally connected upon a parallel horizontal pivotal axis with the forward end of said rearward boom section, a cutter bar supporting head pivotally supported upon the forward end of the front boom section for tilting movement upon an axis parallel to said first and second mentioned axes, a cutting-element-carrying cutter bar swingably supported on said cutter-bar-supporting head for swinging movement in planes parallel to said third mentioned axis, means for holding said bar in different fixed angular relations to said head to which it may be swung, means for moving said head upon said third axis and holding it in different adjusted positions, means extending between the rearward boom section and said support for swinging said rearward boom section upon said first mentioned pivot axis, means for effecting automatically relative swinging of said front boom section relative to the rear boom section when the latter is swung as aforesaid including link means pivotally connected at its opposite ends respectively to said portable support and to said front boom section and having said pivotal connections at opposite sides of the planes defined jointly by said first and second mentioned axes, and means for actuating said cutting elements including a motor driven shaft upon said rearward boom section and driving connections operative in all positions of said boom sections relative to each other and of said head relative to the forward boom section for transmitting power from said shaft to said cutting elements.

5. In combination, a cutter bar, a cutter bar supporting head, a pivotal mounting for said bar on said head, an elongated outer boom section providing a pivotal mounting for said head on an axis extending transversely to the length of said boom section and parallel to the planes of bar swing upon the pivotal mounting of the bar on the head, and means for supporting and swinging said outer boom section and providing automatically for augmented swinging thereof including an elongated inner boom section, means providing a horizontal pivotal mounting for the latter at its inner end, means pivotally connecting the inner end of the outer boom section to the outer end of the inner boom section on a parallel pivot, a tie-forming element connected to the outer boom section at a point above the pivotal connection of the latter with the inner boom section and at a spaced point having a stationary pivotal support in spaced relation to the pivot for the inner boom section, and means for swingingly raising and lowering the inner boom section including devices exerting directly on said inner boom section a swinging force, said devices pivotally connected to the inner boom section and to a stationary point of reaction.

CHARLES F. OSGOOD.

CERTIFICATE OF CORRECTION.

Patent No. 2,284,677.

June 2, 1942.

CHARLES F. OSGOOD.

It is hereby certified that error appears in the printed specification of the above numbered patent requiring correction as follows: Page 1, first column, line 25, for "objections" read --objects--; page 2, second column, line 75, and page 3, first column, lines 1 and 2, strike out the words and period "Due to the particular arrangement of the driving gears with respect to the pivotal axes chain 53."; page 5, second column, line 24, for "thee" read --the--; page 6, first column, line 46, for "conduit 245" read --conduit 235--; and that the said Letters Patent should be read with this correction therein that the same may conform to the record of the case in the Patent Office.

Signed and sealed this 22nd day of September, A. D. 1942.

Henry Van Arsdale,

Acting Commissioner of Patents.
